(57) **CLAIM**

The ornamental design for a coaxial connector receptacle, as shown and described.

DESCRIPTION

FIG. 1 is front view of a coaxial connector receptacle showing our new design;

FIG. 2 is a left side view thereof;

FIG. 3 is a right side view thereof;

FIG. 4 is a top plan view thereof;

FIG. 5 is a bottom view thereof;

FIG. 6 is a front, left side, top plan perspective view thereof; and,

FIG. 7 is a right side view shown in a state of use.

A back view is omitted because the back view is symmetrical to the front view.

The dash-dash broken lines in the drawing are for the purpose of illustrating environmental structure that form no part of the claimed design.
